UNITED STATES PATENT OFFICE.

SAMUEL GOLDBERG, OF NEW YORK, N. Y., ASSIGNOR TO UNIVERSAL FIXTURE CORPORATION, OF NEW YORK, N. Y., A CORPORATION OF NEW YORK.

DISPLAY FIXTURE.

Application filed August 16, 1923. Serial No. 657,723.

To all whom it may concern:

Be it known that I, SAMUEL GOLDBERG, a citizen of the United States, and resident of the borough of Manhattan, in the city, county, and State of New York, have invented certain new and useful Improvements in Display Fixtures, of which the following is a specification.

This invention relates to improvements in display fixtures, and has for its objects to provide a strong and durable fixture of light weight and inexpensive construction which may be readily knocked down for storage or shipment and may be easily assembled for use; to provide a fixture of the hinged leaf or panel type in which the series of hinged leaves or panels may be revolved bodily step by step about a vertical axis; to provide a fixture having hinged article holding panels and a rotatable support therefor so constructed that each two adjacent panels may be swung wide apart and in which the support may be readily rotated through the medium of any one of the panels; to provide an improved construction of article holding panels; to provide sign-holding means for a revolving display fixture; and to provide a compact fixture of large capacity for effectively holding and exhibiting articles of various kinds, such as embroidery packages, pattern packages, handkerchief packages, phonograph record packages, post cards, books, and similar flat articles or articles packed for sale in envelopes or flat boxes.

In the accompanying drawings,

Figure 1 is a perspective view of a display fixture embodying the invention;

Fig. 2 a detail vertical sectional view of the fixture;

Fig. 3 and Fig. 4 detail views showing the upper faces of the upper and lower heads respectively of the revolving spool-like support for the swinging leaves or panels;

Fig. 5 a horizontal section on the line 5—5 of Fig. 2;

Fig. 6 a bottom plan view of one of the hinged leaves or panels, on an enlarged scale;

Fig. 7 a detail perspective view on an enlarged scale showing the lower portion of one of the leaves or panels;

Fig. 8 a perspective view showing a slightly modified form of panel; and

Fig. 9 a perspective view of the sign holder.

The base of the fixture comprises a central, vertically disposed, tubular portion 1 provided with four downwardly and outwardly extending legs 2, and also formed with an internal shoulder 3 at its lower end. The base preferably consists of an integral metal casting. A long vertical standard 4 of tubular form, preferably consisting of a length of rigid metal pipe, is rigidly but detachably supported on the base. The lower end of the tubular standard 4 extends into the bore of the tubular part 1 of the base and seats on shoulder 3. A pair of vertically spaced set screws 5 are tapped through the part 1 and a second pair of vertically spaced set screws 6 are tapped through part 1 at an angle to the screws 5. By tightening the two pairs of screws the standard 4, even when somewhat smaller in diameter than the bore of part 1, may be securely locked to the base against both vertical and rotary movements.

The base 1 may be placed either upon a floor or a counter, and in order to present the panels at the most effective level the rotatable panel carrier is preferably adjustable vertically on the long standard 4. A simple and efficient way of removably and adjustably mounting the carrier is shown. The carrier comprises a relatively long tubular metal barrel or sleeve portion 7 adapted to be slid endwise on and off the standard 4 and to revolve about said standard, said barrel having integral end flanges or disk-like heads 8 and 9 of relatively small diameter. A removable metal collar 10 is adapted to be rigidly locked on standard 4 at any desired level above the base by means of a set screw 11. The collar 10 and carrier head 9 are formed with complementary annular ball-races 12 and 13 in which travel a series of ball bearings 14. The carrier head 8 is provided with a circular series of holes 15 and head 9 is provided with a circular series of holes 16 registering with holes 15, the said holes 15 and 16 receiving the upper and lower ends of the pivot rods 17 of the swinging article-holding leaves or panels.

Each panel comprises a rigid, unitary metal structure of skeleton form, made of light weight stock, but so constructed as to be capable of sustaining a considerable load.

Each panel comprises a vertical series of three-sided channel frames or pockets 18, a pivot rod 17, a pair of stiffening bars 19, a stop member 20, and a pair of pivot-rod embracing straps 21. Each pocket or article-holding frame 18 is formed of a single piece of sheet steel of channel form in cross-section bent to form a frame having a vertical inner end wall and horizontal top and bottom walls all provided with article retaining edge flanges, the free outer end of the pocket being open to permit articles to be slid endwise into and out of the pocket. The top wall of each frame or pocket 18 is spot welded at a plurality of points, as indicated at 22 in Fig. 7, to the bottom wall of the next higher pocket. The edge flanges of all the pockets of the panel are spot welded at 23 to the two vertical sheet metal bars 19 which are arranged at opposite faces of the panel at the free end thereof. The rod 17 is spot welded at 24 to the vertical inner wall of each pocket of the panel midway between the side faces of the panel so that said rod serves both as a pivot post and as a stiffening member for the inner end of the panel. The straps 21 are spot welded to the vertical end walls of the top and bottom pockets at 25 and serve to assist in rigidly holding rod 17 to the row of pockets adjacent the ends of the rod. The stop 20 consists of a narrow strip of sheet metal spot welded at 26 to the bottom wall of the lower pocket at the inner end of the pocket and midway between the side faces of the pocket. I prefer to make the lowermost pocket, or several of the lower pockets, of each panel, of greater height and length than the remaining pockets to adapt the lower pockets of the fixture to receive larger packages or articles. In the drawings only the lower pocket of each panel is shown enlarged. As shown more clearly in Fig. 2, the upper end of pivot rod 17 projects beyond the top of the panel a greater distance than the lower end of said rod projects beyond the bottom of the panel, whereby each panel may be readily attached to the carrier by passing the upper end of the rod up through one of the holes 15 in head 8 of the carrier and then lowering the panel until the lower end of the rod passes through the registering hole 16 in head 9 and stop plate 20 seats on the flat upper face of head 9. The carrier head 9 is provided on its upper face with a circular series of short stop lugs or projections 27 arranged in pairs with the two lugs of each pair located at opposite sides of one of the pivot rod apertures 16. The stops 27 are preferably located slightly nearer the periphery of the head 9 than are the apertures 16, as shown more clearly in Figs. 4 and 5, and each pair of stops are spaced apart a sufficient distance to permit each panel to swing through an arc of ap-

proximately 90 degrees. Each two adjacent panels may thus be swung apart approximately 180 degrees to present the panels edge to edge in substantially the same vertical plane like the two exposed pages of an 70 opened book.

The swinging movement of each panel is limited by the engagement of opposite side edges of its stop plate 20 with the adjacent pair of stops 27, said stops being the same 75 height as the thickness of plates 20, or slightly less in height than the thickness of said plates, so that the rear ends of the panels may swing over the stops 27 as shown in Fig. 5. It will be obvious that the carrier may be rotated step by step through the medium of each succeeding panel by first swinging the panel nearest the observer in one direction until stop 20 engages one of the stops 27 and then continuing to push or 80 pull on the panel in the same direction to cause the series of panels and the carrier to revolve bodily about standard 4. First one face and then the other of each panel may thus be presented before the observer, and each time one face of one panel is exposed the adjacent face of the next panel is simultaneously exposed and practically in open book form as the revolving movement of the carrier causes the following panels to 90 automatically assume tangential positions as indicated in Fig. 5 wherein the fixture is shown at the end of a clockwise rotary movement to open up two panels.

The pockets or frames 18 are preferably 100 made relatively thick so as to adapt the same to receive at least two articles back to back so the faces of the two articles will be exposed at opposite faces of the panel. Preferably the pockets are of sufficient thickness 105 to receive duplicate articles or packages between the two outer articles or packages.

In Fig. 8 a slightly modified form of panel is shown especially adapted for holding relatively heavy and fragile packaged goods 110 such as phonograph records in the usual paper envelopes. This panel is constructed precisely as the panels above described except that the pockets 18 are slightly elongated vertically instead of horizontally to 115 receive the square envelopes containing the disk records, and each pocket is provided at the outer end of its bottom wall with a narrow U-shaped metal package-retainer 28, the front cross-bar of which extends across 120 the outer edges of packages in the pocket near the lower edges of said packages. The side arms of the retainer rest on the bottom wall of the pocket and are welded to the edge flanges of said wall. By providing vertically elongated pockets with projecting retainers 28, square packages may be securely retained in panels of less width than the articles, thus economizing in weight and material and cost of manufacture of the fix- 130

ture. The retainers also prevent outward movement of the relatively heavy phonograph record packages under the influence of centrifugal force when the fixture is revolved rapidly, thus preventing the record packages from flying out of the pockets.

An important feature of the present invention consists in the provision of simple means for effectively displaying in connection with the fixture an advertising card or cards, such as a card announcing a special sale of articles contained in the fixture and the price thereof. The card holder shown comprises a long vertical metal rod 29 and two horizontal rods 30 and 31 extending transversely of rod 29 and welded thereto one above the other at 33 and 34. The rod 30 crosses rod 29 close to the top of rod 29 and projects only a short distance at either side of rod 29, while rod 31 is relatively long and crosses rod 29 preferably between the middle of the rod 29 and the upper end of said rod, thus leaving a long unobstructed lower section of the rod 29 adapted to telescope more or less within the upper end of the tubular standard 4. The card holder is locked in its vertically adjusted positions by means of a set screw 32 tapped through the standard 4 and adapted to be screwed against rod 29. The sign or advertising card 35 is suspended by a cord loop 36 extending up in front of rod 30 and over said rod and dropped over the upper end of rod 29. The back of the card rests against rod 31 and rod 29 and is thus held against swinging movement with the face of the card turned in the desired direction. It will be obvious that a second card may be hung at the opposite side of the holder if desired. It will be noted that by adjusting the holder vertically cards of different sizes may be effectively supported above the holder. It will also be noted that the holder does not revolve with the carrier and pockets but always presents the face of the card in the same direction. The holder may be readily removed by loosening screw 32 when the fixture is knocked down.

The stiffening bars 19 afford convenient means whereby the panels may be grasped to swing the panels and to rotate the carrier. While a card holder substantially in the

form of a patriarchal cross is shown and described herein, it will be evident that other forms of sign holders may be mounted on the standard 4.

What I claim is:

1. A display fixture comprising a spool-like carrier, means supporting the carrier to rotate about a vertical axis, a series of swinging panels extending outwardly from the carrier and pivoted at their inner ends between the upper and lower heads of the carrier, each panel being formed with a series of superposed article-holding pockets open at their sides and at their outer ends, a stop carried by the lower end of each panel and riding upon the lower carrier head, and a series of spaced abutments carried by the lower carrier head and arranged in pairs with one abutment at either side of each of said stop members to limit the swing of the panels relatively to the carrier by contact with the stop members, the stop members spacing the panels above the abutments and being of materially less width than the transverse width of the panels to increase the swinging scope of the panels.

2. A display fixture comprising a base, a vertical post supported by the base, a vertical spool-like carrier rotatably mounted on the post, a series of swinging article-holding frames extending outwardly from the carrier and pivoted at their inner ends between the upper and lower spool heads and each formed of a series of superposed channeled pockets having their outer ends open, an abutment member rigidly carried by each of said frames at one end between the frame and one of the spool heads, and a series of stop lugs rigidly carried by the spool head adjacent said abutment members of the frames and arranged in pairs with one lug at either side of each abutment member, the abutment members being adapted to abut the stop lugs when the frames are swung on their pivots and being of materially less width than the transverse width of the frames to increase the swinging scope of the frames.

In testimony whereof I hereunto affix my signature.

SAMUEL GOLDBERG.
